US00D568331S

(12) **United States Design Patent** (10) **Patent No.:** **US D568,331 S**
(45) **Date of Patent:** **** May 6, 2008**

(54) **GENERATED IMAGE FOR DISPLAY ON A PERSONAL DIGITAL ASSISTANT**

(75) Inventor: **Kyu-Sung Kim**, Seoul (KR)

(73) Assignee: **Samsung Electronics Co., Ltd.**, Suwon, Kyunggi-Do (KR)

(**) Term: **14 Years**

(21) Appl. No.: **29/286,894**

(22) Filed: **May 22, 2007**

(51) LOC (8) Cl. **14-04**

(52) U.S. Cl. **D14/487**

(58) Field of Classification Search D14/485-495;
715/700-867, 973-977

See application file for complete search history.

(57) **CLAIM**

The ornamental design for a generated image for display on a personal digital assistant, as shown and described.

DESCRIPTION

FIG. 1 is a top front perspective view of a generated image for display on a personal digital assistant showing my new design;

FIG. 2 is a front elevational view thereof; and,

FIG. 3 is an enlargement of the image area shown in FIG. 2. The broken lines are for illustrative purposes only and form no part of the claimed design.
